UNITED STATES PATENT OFFICE.

WILLIAM J. HAERTHER, OF NEW YORK, N. Y., ASSIGNOR TO FIBRE SHIPPING TUBE CORPORATION, OF NORTH ADAMS, MASSACHUSETTS, A CORPORATION OF DELAWARE.

KNOCKDOWN SHIPPING TUBE.

Application filed March 25, 1922. Serial No. 546,820.

To all whom it may concern:

Be it known that I, WILLIAM J. HAERTHER, a citizen of the United States, residing at New York, in the county of New York 5 and State of New York, have invented new and useful Improvements in a Knockdown Shipping Tube, of which the following is a specification.

My invention relates to new and useful 10 improvements in a knockdown shipping tube, and has for its object to provide a device of this character for shipping rolls of paper, linoleum, rugs and the like so as to protect such articles against damage and 15 prevent the ends from being torn, cracked or bent.

Another object of the invention is to provide a shipping tube of the class stated which may be collapsed and the parts nested 20 in one another when empty so as to occupy a small amount of space for return to the shipper.

A further object of the invention is to form such a container from two semi-tubular members the longitudinal edges of 25 which form butt joints with an internal flange at each end against which suitable caps are held in contact with the flanges by the object or article placed in the container and means for holding the semi-tubular sections in their set up positions, 30 said means being preferably wire bales although any equivalent such as metal bands or straps could be substituted.

With these ends in view, this invention 35 consists in the details of construction and combination of elements hereinafter set forth and then specifically designated by the claims.

In order that those skilled in the art to 40 which this invention appertains, may understand how to make and use the same, I will describe its construction in detail, referring by numerals to the accompanying drawings 45 forming a part of this application, in which:

Fig. 1, is a perspective view of a knockdown shipping tube embodying my invention.

Fig. 2, is an enlarged section at the line 2-2 of Fig. 1, looking in the direction of the arrows.

Fig. 3, is a similar view at the line 3-3 of Fig. 1.

Fig. 4, is an enlarged fragmentary longi-

tudinal sectional view of one end of the shipping tube in its set up position.

Fig. 5, is a perspective view similar to Fig. 1, showing the semi-tubular sections nested for return shipment.

In carrying out my invention as here embodied, 4 and 5 represent two semi-tubular members formed of any suitable material in any well known or preferred manner although here shown as built up of a number of spirally wound layers in the same manner as the well known mailing tube is made. In actual practice a tube is first produced and then split longitudinally to produce the two members.

On the inside of each of the semi-tubular members at or adjacent their ends are located the semi-circular flanges 6 thereby forming shoulders 7 a short distance inside or short of the ends.

The longitudinal edges of the semi-tubular members when the latter are set up, as shown in Fig. 1, form a butt joint as will be obvious and said members are guided or positioned by means of the caps 8 which snugly fit the interior of the tubular members and contact with the shoulders 7 produced by the inner edges of the flanges 6, said caps being maintained in their positions by the contact of the ends of the article or object in the container with said caps.

In order to hold the parts in their set up positions, as shown in Fig. 1, a plurality of bales or ties 9 are wrapped about the exterior of the tube and the ends fastened together in any suitable manner, the ties being here shown in the form of wires with the ends twisted about one another for fastening purposes.

As these shipping tubes are preferably made of card board or like material they have a certain amount of resiliency or flexibility so that one semi-tubular member may be nested within another by slightly expanding one and compressing another as will be readily understood. When the two members are nested as shown in Fig. 5 they occupy less space than when in a set up position, as shown in Fig. 1, and when in this condition may be returned to the shipper at small expense.

When packing an article or object in one of the shipping tubes one of the semi-tubular members may be laid upon a suitable supporting surface, such as a floor of a building,

and the article or object placed therein either before or after the caps 8 have been set in place. The other semi-tubular member is then placed over the article and positioned so that the caps 8 are inside of the flanges of said member which will permit the longitudinal edges of said members to contact with one another. Next the ties or bales 9 are placed about the completed tube and 10 drawn taut so as to rigidly hold the parts in place.

As an example for illustrating the advantages of a shipping tube constructed in this manner I will presume that a roll of high 15 grade or expensive paper is the article or object contained in the tube. The workmen handling this class of goods will often 20 end the roll causing the edge of the paper to be mashed, torn or otherwise damaged so that the purchaser is compelled to cut off as 25 waste a strip of considerable width and length along both edges so that a considerable part of the paper will not then cut up into uniform sized sheets producing an enormous loss to large users of this class of 30 paper. Further under present day methods such a roll of paper is wrapped with many layers of wrappings of a cheaper grade paper which is a complete loss to both the shipper and purchaser.

These are disadvantages which are entirely or partially eliminated by the use of my device because the tube being of very stiff 35 material the ends are unlikely to be mashed or damaged and even though the ends of the tube are damaged it will not affect the contents because of the distance between the ends of the tube and the caps and therefore

the roll of paper will reach the purchaser in good condition. Since the tube may be 40 nested and returned to the shipper it may be used over again and again so that the expense on any one shipment is very small and which it is thought will considerably 45 overbalance the cost of a paper wrapper. 45

Of course I do not wish to be limited to the exact details of construction as herein shown as these may be varied within the limits of the appended claims without departing from the spirit of my invention. 50

Having thus fully described my invention, what I claim as new and useful is:—

1. In a device of the character stated, two separate semi-tubular members adapted to be nested one within another or set up to 55 form a tube, means for holding said members in a set up position, semi-circular internal flanges located at each end of each member, and caps fitting within the tube formed from the aforementioned members 60 and contacting with the inner portions of the flanges by which said caps are prevented from outward displacement.

2. In a device of the character stated, a pair of separate semi-tubular members, a 65 semi-circular flange at each end of each member, said members adapted to be telescoped or nested one within the other or set up in opposed relation to produce a tube, caps within the tube thus formed, said caps being held against outward displacement by the flanges, and ties secured about the completed tube for holding the parts in place. 70

In testimony whereof, I have hereunto affixed my signature.

WILLIAM J. HAERTHER.
